SHOE SOLE LAYING AND LASTING MACHINE

Meyer Siegel, Chicago, Ill., assignor to Monarch
Shoe Company, Chicago, Ill., a corporation of
Illinois

Application October 19, 1936, Serial No. 106,405

2 Claims. (Cl. 12—7)

The invention relates to improvements in shoe sole laying and lasting machines and has for its primary object the provision of an improved machine or appliance of the character indicated which is capable of economical production and highly efficient in use.

Another object of the invention is the provision of a construction of the character indicated so constructed and arranged as to facilitate the proper shaping of a shoe and fitting of the sole thereto.

Other objects will appear hereinafter.

The invention consists in the combinations and arrangements of parts hereinafter described and claimed.

The invention will be best understood by reference to the accompanying drawings forming a part of this specification and in which

Fig. 1 is a side view, shown partially in section, of a machine or appliance embodying the invention;

Fig. 2, an enlarged partial top plan view of the same;

Fig. 3, an enlarged side view of the main portion of the construction;

Fig. 4, a front view corresponding with Fig. 3;

Fig. 5, a horizontal section taken substantially on line 5—5 of Fig. 4; and

Fig. 6, a longitudinal section corresponding with

Fig. 5.

The embodiment of the invention illustrated in the drawings comprises a suitable supporting frame 10 generally in the form of a table. A vertical last spindle 11 is arranged as shown on the top of said table 10 adjacent the front edge thereof. The spindle 11 is carried by the base block 12 vertically slidable on a post 13' on a second base block 13 secured as indicated to a plate 10' mounted on top of the table 10. Associated with the spindle 11 is a laterally swinging hand lever 14 carrying an inclined cam plate 15 arranged to be inserted as shown between the supporting base 12 and the base 13 to adjust the former vertically on the post 13'.

The spindle 11 is arranged as best shown in Fig. 6 to receive a shoe last 16 of usual construction and carrying a shoe 17 in the course of manufacture, said shoe last being provided with a socket 18 to receive the upper end of the spindle 11, said shoe last and shoe thereon thus being rendered vertically adjustable on the spindle 11 by means of the cam plate 15 as will be readily understood.

Associated with the spindle 11 is a swinging arm 19 hinged as shown to the top of the table 10

provided at its upper end with a padded toe support 20 adapted and arranged to be adjusted to the toe portion of the last 16 to support the same and the shoe thereon during the lasting operation. For convenience of adjustment the base block 13 and the arm 19 are both mounted on the adjustable plate 10' which is adjustably mounted in suitable guides on the table top and the arm 19 is further rendered adjustable on the plate 10' by means of a pin 19' adapted and arranged to engage spaced openings in the plate 10' as best shown in Fig. 6.

Two laterally swinging clamping plates or "wipers" 21 are arranged as shown on opposite sides of the last 16, each clamping plate being provided with a curved edge 22 nicely shaped as best shown in Fig. 5 to the contour of the corresponding sides and around the heel of the shoe on the last. The clamping plates 21 are secured as shown in slots in clamping levers 23 pivoted at 24 opposite the central part of toe portion of the last and whereby said clamping plates 21 are arranged to swing toward and away from the last in planes just below the welt of the shoe on the last. At their forward ends the clamping levers 23 are provided with inward extensions 25 connected with handle members 26 arranged to be secured together in their innermost portion by a latch member 27 as best shown in Fig. 2. By this arrangement a shoe member on the last 16 may be readily clamped to the last by means of the clamping plates 21 and said clamping plates securely locked in clamping position as will be readily understood.

A clamping loop in the form of a flexible wire 28 is arranged as shown to embrace the toe portion of the shoe just under the welt, the ends of said loop passing thence downwardly through slots 29 in the edges of the plates 21 around the guide member 30 in guide grooves 31 and are connected at their lower ends with a belt 32 which in turn is connected with a foot lever 33 and whereby the wire loop 28 may be tightly drawn about the last in order to hold the shoe member in proper position thereon.

In use and in operation a pre-welt shoe comprising the usual upper, insole and welt are preferably secured to the last 16 by nails and said last is then placed on the spindle 11 and nicely adjusted thereon until the plane of the clamping plates 21 is arranged to pass just under the welt of the shoe. The edges of the plates 21 are then fitted around the shoe just under the welt, the wire loop 28 fitted around the toe portion of the shoe also just under the welt and

said clamping plates and wire loop simultaneously tightened about the shoe to shape and hold the same in place on the last as will be readily understood by those skilled in the art. Owing to the fact that the clamping members are pivoted at points opposite the central part of the toe portion of the last, the portions thereof shaped to fit the shoe sides are first brought into positive clamping engagement therewith so as to 5 secure the uppers at these points, before the stretching action of the upper around the heel is completed thus greatly facilitating a close fit at the sides. Then when the flexible loop is tightened around the toe portions, these portions of 10 the upper are stretched forwardly from the side portions thus greatly facilitating a smooth fit at the toe portions. Then the nails securing the insole in place on the last are withdrawn; adhesive is applied to the insole and welt and the outer 15 shoe sole applied by heavy pressure and pounding to be accurately and nicely secured in place. When this has been done the shoe is in condition for removal and sewing and trimming of the sole. The removal of the last and shoe is also greatly facilitated by further manipulation of the lever 14.

By this arrangement the shoe soles may be glued in the same machine or appliance in which the lasting is done; the clamping plates are a part of the lasting and sole laying mechanism; and heavy pressure and pounding is permissible for the purpose of building the shoe properly owing to the proper adjustment of the last permitted by the mechanism and the presence of the adjustable padded toe rest disclosed. The specific form and arrangement of parts is a simple and effective one for the purpose.

While I have illustrated and described the pre-

ferred form of construction for carrying the invention into effect, this is capable of variation and modification without departing from the spirit of the invention. I, therefore, do not wish to be limited to the precise details of the construction set forth, but desire to avail myself of such variations and modifications as fall within the scope of the appended claims.

I claim:

1. A device of the class described comprising a shoe last support; a pair of clamping members positioned on opposite sides of and pivoted at points opposite the central part of the toe portion of the support to swing toward and away from the same and shaped to fit the corresponding shoe sides and around the heel thereof; means for forcing said clamping members toward said support; means for locking said clamping members in clamping positions; a loop of flexible material arranged to embrace the toe portion of a shoe; and means for drawing said loop tightly around the toe portion of the last support.

2. A device of the class described comprising a shoe last support; a pair of clamping members positioned on opposite sides of and pivoted at points opposite the central part of the toe portion of the support to swing toward and away from the same and shaped to fit the corresponding shoe sides and around the heel thereof; means for forcing said clamping members toward said support; means for locking said clamping members in clamping positions; a loop of flexible material arranged to embrace the toe portion of the shoe, the ends of said loop passing downwardly through openings in said clamping members; and means for drawing said loop tightly around the toe portion of the last support.

MEYER SIEGEL.
